CIRCUIT INTERRUPTER

Herbert L. Rawlins, Wilkinsburg, and William H. Cuttino, Pittsburgh, Pa., assignors to Westinghouse Electric & Manufacturing Company, East Pittsburgh, Pa., a corporation of Pennsylvania

Application October 18, 1934, Serial No. 748,802

11 Claims. (Cl. 175—298)

Our invention relates, generally, to expulsion circuit interrupters and is particularly concerned with the provision of improved mounting arrangements for such apparatus.

5 While expulsion circuit interrupters take a multitude of forms, the so-called expulsion fuse is probably the best known example of these devices. Ordinarily, an expulsion fuse consists of a tubular member for defining the walls of an 10 arc passage, a fusible element for establishing an arc within that passage, and a means for causing a blast of arc extinguishing gas to flow longitudinally through the arc during the arc extinguishing operation. The blast of arc extinguishing gas is most readily secured by lining the arc passage with a material which is capable of evolving a suitable gas when placed in proximity to an electric arc, and to make the blast most effective, the tube is preferably closed 15 at one end.

20 Expulsion fuse devices, such as those described above, have proven themselves very satisfactory and very reliable in operation when used out of doors, or in locations where space is not an important consideration. However, when the devices are utilized in restricted places, several complications arise. First, the gas which is explosively ejected from the fuse tube during the arc extinguishing operation is usually rather highly 25 ionized and thus semi-conducting. If such gas is allowed to contact adjacent live parts serious short circuits may be produced, with considerable resultant damage to the involved equipment. And second, due to space limitations, the fuses 30 are usually mounted on two supporting insulators in such manner that the reaction forces of the out-flowing gas blast produced within the tube during the interruption of very large over-loads produce cantilever stresses on those insulators. Frequently, the magnitude of these 35 stresses becomes sufficiently great to create a serious danger that the supporting insulators will be cracked or even entirely broken, and in many installations, due to the risk of possible failure 40 of the fuse supports, more costly oil switches have had to be utilized.

45 One application for which expulsion fuses are particularly suitable is for the interconnecting of the individual capacitance units of a power type capacitor, such as those used for power factor correction. In this service, space is almost always an important consideration and the usual high voltages involved so seriously complicate the problem of circuit interruption that a high 50 capacity breaker must be used; oil or other liquid

type breakers are impractical both because of their size and cost, and the most feasible solution appears to be in the use of expulsion devices.

5 The prior art structures utilized expulsion type interrupters in conjunction with numerous complicated arrangements for interconnecting the capacitance units, but none of the arrangements so far developed has been quite satisfactory. In the interests of economy, it is most desirable that the fuses be supported upon the terminal insulators of the capacitors themselves, but the prior art fuses, due to their size, have always had to be mounted at such an angle that cantilever stresses were induced in those insulators during the circuit opening operation. Frequently, the insulators 10 were broken as a result of these stresses, and the out-flowing gases often contacted adjacent live parts with the result that short circuits developed. Further, the fuses were usually mechanically connected to the strap conductors 15 which interconnect the capacitance units and these conductors were many times bent in such manner that the re-straightening of them became 20 impractical or quite impossible.

25 As mentioned above, interconnecting means for this type of service preferably include expulsion fuses or like devices for disconnecting individual units from the associated circuit upon the failure of the insulation within that unit, or upon the occurrence of other predetermined conditions. To overcome the disadvantages of the prior art devices, the means for supporting the 30 expulsion fuses should be so arranged that the strap connectors are subjected to substantially no stress during the opening operation of the 35 fuses. Also, the reaction forces exerted by the fuse should not subject the supporting insulators to any substantial cantilever stress, and the out-flowing gas should be directed away from the 40 capacitance units and the adjacent live parts.

45 The primary object of our invention is to provide a structure capable of meeting the requirements which shall be simple in design and relatively inexpensive to manufacture.

This object of our invention is accomplished 45 through the provision of a novel means for interconnecting the individual capacitance units with each other, and with the associated apparatus. By mounting the expulsion fuses vertically 50 upon the supporting insulators for the terminals of the capacitance units, all cantilever stresses are eliminated, and the out-flowing blast of arc extinguishing gas is directed away from the live parts of the apparatus. Further, through the provision of novel means which we will describe 55

in some detail later, the strap members which serve to interconnect the several units are subjected to substantially no stress during the operation of the fuse devices.

- 5 In order to further reduce the reaction forces exerted by the fuses, we prefer to utilize a device wherein the arc extinguishing gases are, for the most part, condensable. If this is done, a condenser means may be added to the expulsion fuse
 10 structure, for controlling the out-flow of the arc extinguishing gas, and this device, by condensing at least some of the arc extinguishing gas minimizes both the possibility of the development of excessive pressures within the fuse and the
 15 reaction forces exerted by the outflowing gases.

A further object of our invention is to provide an improved means for mounting expulsion fuses or similar devices, our improved mounting means to utilize but a single supporting insulator and
 20 to include means for preventing cantilever stresses from being induced in that insulator during the operation of the fuse.

A still further object of our invention is to simplify the structure of capacitor devices generally and to increase their reliability of operation.
 25

These and other objects of our invention will be made more apparent by reference to the following drawings and description wherein we have particularly set forth the structural features of a preferred embodiment of our invention.
 30

Referring to the drawings:

Figure 1 is an elevational view of a three-phase capacitor structure embodying the principal features of our invention. A considerable portion of one of the sides of the main closure has been cut away in order to more clearly illustrate the structural features involved;
 35

Fig. 2 is a plan view of the capacitor device shown in Fig. 1. Similar to that figure, a substantial portion of the closure has been cut away;
 40

Fig. 3 is a sectional view taken on the line III—III of Fig. 2;

Fig. 4 is a fragmentary perspective view showing one of the interconnecting arrangements utilized in the prior art structures;
 45

Fig. 5 is an enlarged elevational view of one of the expulsion fuse devices which is utilized in this embodiment of our invention;

Fig. 6 is a sectional view through the fuse structure shown in Fig. 5; and
 50

Fig. 7 is a sectional view taken on the line VII—VII of Fig. 5.

The capacitor structure shown in Figs. 1, 2, and 3 comprises, generally, a main closure 1, a plurality of individual capacitance units 3, a means 5 for interconnecting those units, three hollow insulators 7 for permitting the passage of external leads through the closure 1, and three pin type insulators 9, supported on one of the end portions of the closure 1, for providing terminals for the interconnected capacitance units.
 55

As shown in the drawings, the main closure 1 comprises a frame 11 of angle iron and a base plate 12 which are welded together. Suitable top and side members of heavy wire mesh or sheet steel, which are removably supported upon the angle iron frame 11 by suitable screw fastenings or the like, serve to protect the individual units while at the same time permitting ready observation of their condition.
 60

The capacitance units 3 are not an important part of our invention and may take any of the well known forms. As shown, they comprise an
 65

outer metallic casing 13 for enclosing the condenser units, and three hollow porcelain insulators 15 rigidly supported thereon. A conducting member 17, which is threaded on its outer end, extends through each of the insulators in 5 order to provide suitable terminals for each of the units. The metallic cases 13 are electrically interconnected by a strap conductor 16 and suitable cap screws 18.

The means 5 for interconnecting the several 10 capacitance units includes three strap members 19 of flexible conducting material and twelve expulsion fuse devices 21, two of which are associated with each of the capacitance units. One of the strap members 19 is adapted to engage the 15 conducting member 17 which extends through the central insulator 15 of each of the capacitance units and to be electrically and mechanically connected to those members by suitable nuts 23. One of the expulsion fuse devices is 20 supported upon each of the outer insulators 16, and these devices are electrically connected together by the two other conducting straps 19, as will be described later.

Each of the fuse devices 21 includes an arc 25 extinguishing portion and a condenser portion, as shown particularly in Figs. 5, 6, and 7. The outer walls of each of the arc extinguishing portions is defined by a rather thick walled tube 24, of fiber or other mechanically strong insulating 30 material, which is threaded at either end. A hollow cylindrical liner member 25, preferably formed of compressed boric acid or some other material which is capable of evolving an arc extinguishing gas substantially all of which is condensable, when placed in proximity to an electric arc, is disposed within the fiber tube 24 and serves to define the outer walls of the arc passage 27. A plug member 29 of conducting material is threaded into the lower end of the main 40 fiber tube 1 and serves both to close one end of the arc passage 27, and to provide a terminal for the fuse structure itself.

The condenser portion of each of the fuse devices is enclosed within a metallic tubular member 31 which is screwed onto the upper end of the cooperating tube 24. A threaded stud 33 projects outwardly from each of the tubular members to provide an upper terminal for the device, the inner end of this stud engaging a hollow cylindrical conducting member 35 which is adapted to abut against the upper end of the fuse tube 24 and the liner member 25. A pin 37 prevents the stud 33 from disengaging the member 35.
 45

Each of the tubular members 31 is filled with 55 copper shavings or similar material, in order that it may act as a condenser during the normal operation of the fuse device of which it forms a part. The upper end of each of the tubular members 31 is closed by means of a threaded plug 39 of insulating material which has a plurality of openings 41 cut therein in order to prevent excessive pressure from being developed within the condenser during its operation. A flat circular member 43 of insulating material is normally positioned on top of each plug member 41 in order to close the upper end of the fuse structure. Preferably the member 43 is retained in place by an adhesive or some other means which will allow it to be moved to open the upper end of condenser to the atmosphere upon the development of a predetermined pressure within the fuse device. Through this arrangement, the member 43 can be used as an indicator for showing when the associated fuse has operated.
 60
 65
 70
 75

- A fusible element 45 is provided for completing the electrical circuit between the lower plug member 29 and the upper terminal (the outwardly projecting stud 33) of each of the fuse devices. 5
 5 The lower end of each of the fusible elements extends into a suitable opening 49 formed within the cooperating plug member and is soldered therein, and the upper end of each of the fusible elements is soldered to a terminal portion 51 10
 10 which is connected to the adjacent cylindrical conducting member 35 by a suitable screw 53.

The lower end of each of the plug members 29 is provided with a threaded opening 55 for engaging the threaded end of the conducting member 17 which extends through each of the insulators 15 supported upon the capacitance units 3. Through this arrangement, each of the fuse devices 21 is entirely supported upon one of the insulators which provide terminals for the 20 capacitance units.

By providing a separate fuse device in series with the electrical circuit connecting each of the capacitance units with the associated equipment, the maximum possible protection is assured at 25 all times. For example, upon the development of a fault or other abnormal condition within any one of the individual capacitance units the associate fuse immediately removes that unit from the circuit and allows the remaining sound units, 30 connected in parallel therewith, to function in the normal manner.

Since the end of each of the expulsion fuse devices 21 which is open during the circuit interrupting operation is positioned away from the 35 capacitance units and the means for interconnecting those units, substantially all of the gas which is liberated during the normal operation of these devices is caused to vent away from the live parts of the apparatus, thereby assuring that 40 voltage breakdown or short circuits will not result. The axis of the arc passage 27 through each of the expulsion fuse devices substantially coincides with the axis of the conducting member 17 extending through the cooperating supporting 45 insulators therefor. By virtue of this, the ceramic portions of the several insulators 15 are subjected only to compressive stresses during the circuit opening operation of the fuses. This arrangement, through the elimination of cantilever 50 stresses, effectively prevents any cracking of the insulators 15, ordinary ceramic materials being comparatively strong in compression, although they are comparatively weak when subjected to cantilever stresses.

In order to minimize the reaction forces which 55 are exerted by the individual fuse devices during the circuit opening operation, each of the arc passages 27 is lined with a material which is capable of evolving an arc extinguishing gas, substantially all of which is condensable in nature, when placed in proximity to an electric arc. The preferred material, boric acid is particularly satisfactory, but other substances capable of evolving condensable gases may be used. When such a 60 lining material is used, the condenser may be so proportioned that a very considerable portion of the outflowing gases may be condensed within the fuse itself, and as a result much of the reaction force normally exerted by expulsion devices 65 is effectively eliminated. Further, substantially all of the out-flowing gases may be readily cooled sufficiently to render them non-conductive, and as a result, a much safer and much more reliable device is made possible.

75 A fragmentary perspective view of one of the

prior art devices is shown in Fig. 4. In this structure, each of the capacitance units 103 is provided with only two terminal insulators 115, it having been found undesirable in these structures to attempt to utilize a double section unit, 5 due to the fact that it was difficult to secure sufficient spacing of the insulators to accommodate the fuse devices without unreasonably and unnecessarily increasing the size of the units themselves. The inner terminals of each of the 10 groups of two units are connected one to another by means of straps 119 of conducting material, and these straps are, in turn, interconnected by a third strap member 121 also of conducting material. A porcelain insulator 123 is 15 supported upon each of the short straps 119, and these insulators serve to support a bus structure which includes a longitudinally extending conducting member 125 and a plurality of laterally extending conducting members 127. A single 20 fuse 129 is provided for each of the capacitance units. One end of each of these fuses is affixed to the outer insulator 115 of the associated unit, and the other end engages one of the lateral strap members 127. 25

Due to the length of the prior art fuse devices, the fuses 129 were always mounted at a substantial angle with respect to the longitudinal axis of the insulators 115. Further, their mounting was not rigid. Upon the occurrence of a fault 30 condition within any one of the capacitance devices, the fuse 129 protecting that portion of the circuit blew in the customary manner, and the arc extinguishing gas was liberated either at the upper end or the lower end of the fuse tube. 35 Since at least one of the terminals of each of the fuses engaged the conducting means utilized for connecting that fuse into the circuit, the reaction forces produced during the circuit interrupting operation often caused serious bending 40 of the interconnecting means, frequently resulting in sufficient damage to that means to necessitate its being completely removed when the unit was serviced. Moreover, the extreme length of the prior art fuse devices and their resulting 45 angular displacement with respect to the axis of the supporting insulators 115, resulted in the production of large cantilever stresses during the interruption of abnormal overloads and the like, which stresses often caused the breaking or the 50 cracking of those insulators.

The advantages of our invention over this arrangement are obvious. Each of the expulsion fuse devices 21 is mounted so that the gas blast resulting from the operation of that device is 55 directed away from the exposed live parts of the associated apparatus, and so that substantially no force is exerted upon any of the conducting members utilized for interconnecting the several units during the operation of the fuse. In addition, the reaction force of the fuse devices produces substantially no cantilever stresses in the supporting insulators therefor. The resultant structure is thus not only much more reliable 60 in operation than the prior art arrangements but in addition it is much more simple in form.

Further, the replacement of the fuse devices following their operation is much simpler in the structure of our invention than in the prior art arrangements. Since the conducting straps are 70 not subjected to any stress they are never bent out of shape when the fuse devices operate, and to replace one of the fuse devices, it is necessary merely to remove one of the nuts which connect the stud 33 to the cooperating strap 19 and then 75

to unscrew the fuse device itself from the conducting member 17.

While in the foregoing we have disclosed how our invention may be utilized in conjunction with connecting means for capacitors, it is to be understood that many of the features of our invention are capable of much wider application. For example, the improved means for mounting expulsion fuse devices on a single insulator is capable of wide general application in the art. It is our desire, therefore, that the language of the accompanying claims shall be accorded the broadest reasonable construction, and that our invention shall be limited only by what is expressly stated therein, and by the prior art.

We claim the following as our invention:

1. In combination, a plurality of insulator units, each of which includes a means of frangible insulating material and a terminal member rigidly supported thereon, and means for electrically interconnecting said terminal members, each of said terminal members having a threaded portion formed integral therewith, said interconnecting means including strap conductors for interconnecting at least some of said terminal members and a plurality of expulsion fuse devices for disconnecting individual terminal members from said plurality of interconnected members upon the occurrence of predetermined conditions, each of said fuse devices including means for defining an arc passage which is open at one end during the operation of said device, means for drawing the arc incident to the operation of said device within said passage, means for creating an explosive blast of arc extinguishing gas through said arc passage during the arc extinguishing operation, a member of conducting material for closing one end of said arc passage, said member having a threaded portion adapted to cooperate with the threaded portion of one of said terminal members in order that each of said fuse devices may be supported on that terminal member, said cooperating threaded portions being so arranged that the longitudinal axis of the arc passage within each of said devices shall substantially coincide with the longitudinal axis of the insulating means upon which said device is supported, and a means of conducting material extending outwardly from each of said fuse devices adjacent the open end thereof and substantially at right angles to the longitudinal axis of the associated arc passage in order that said fuse devices may be interconnected without placing any of said strap conductors in the normal path of the arc extinguishing gas blast.
2. In electrical apparatus, the combination of a terminal insulator, and a fuse which is adapted to be mounted directly upon said terminal insulator, said fuse comprising a tubular means of insulating material for defining the walls of an arc passage, a threaded member of conducting material which is adapted to close one end of said arc passage and to engage said terminal insulator in such manner that said fuse is rigidly supported thereon, the other end of said arc passage being open at least during the circuit opening operation, means for establishing an arc within said arc passage, means lining said arc passage which is capable of evolving an arc extinguishing gas, a considerable portion of which is condensable, when placed in proximity to an electric arc, and a condenser means entirely supported on said tubular member adjacent said open end for cooling and condensing the outflowing arc extinguishing gas, during the circuit opening operation, in order to minimize the reaction forces exerted by said device on said terminal insulator.

tion, in order to minimize the reaction forces exerted by said device on said terminal insulator.

3. A fuse which is adapted to be mounted directly upon one of the terminals of the apparatus protected by said fuse, comprising a tubular means for defining the walls of an arc passage, a threaded member of conducting material which is adapted to close one end of said arc passage, and to engage one terminal of the apparatus protected by said fuse, the other end of said arc passage being open during the circuit opening operation, means for establishing an arc within said arc passage, means lining said arc passage which is capable of evolving an arc extinguishing gas when placed in proximity to an electric arc, and a means for cooling said gas and for controlling the speed of outflow of said gas, during the circuit opening operation in order to minimize the reaction forces exerted by said device.

4. In electrical apparatus, a terminal insulator therefor which comprises a centrally disposed conductor, threaded at one end, and a ceramic insulating member surrounding said conductor, and an expulsion fuse device for protecting said apparatus and the associated equipment upon the occurrence of abnormal conditions, said fuse being adapted to be entirely supported upon said terminal insulator and comprising a tubular means of insulating material for defining the walls of an arc passage, a threaded member of conducting material which is adapted to close one end of said arc passage and to engage the threaded end of said conductor in such manner that said fuse device is rigidly supported thereon, the other end of said arc passage being open at least during the circuit opening operation, means for establishing an arc within said arc passage, means lining said arc passage which is capable of evolving an arc extinguishing gas, a considerable portion of which is condensable, when placed in proximity to an electric arc, and a condenser means entirely supported on said tubular member adjacent said open end for cooling and condensing the outflowing arc extinguishing gas, during the circuit opening operation, in order to minimize the reaction forces exerted by said device on said terminal insulator.

5. In combination, an insulator, comprising a centrally disposed conductor of substantial length and a means of insulating material surrounding said conductor, an expulsion fuse device, and means for supporting said fuse device on said insulator in such manner that substantially all of the stresses induced therein during the operation of said fuse device are compressive in nature, said fuse device comprising means for defining an arc passage, means for producing an explosive flow of arc extinguishing gas, substantially all of which is condensable, through said arc passage, during the arc extinguishing operation, and a condenser means for condensing at least a portion of said arc extinguishing gas during the arc extinguishing operation in order to minimize the reaction forces exerted by said fuse device on said insulator during the operation thereof.

6. In combination, a plurality of spaced insulator columns which are arranged in such manner that the longitudinal axes thereof are substantially parallel to each other, each of said insulator columns being formed, at least in part, of frangible insulating material; a conducting terminal member supported on each of said insulator columns; a plurality of expulsion fuse devices; means for supporting each of said fuse devices on one of said terminal members; and

5 a common bus bar means, adapted to be entirely supported upon said fuse devices, for electrically interconnecting those devices; said fuse devices being supported on said insulator columns in such manner that substantially all of the stresses induced in said insulator columns during the operation of said fuse devices are compressive in nature and that the arc products expelled from said fuse devices during the operation thereof are directed away from said bus bar means and said insulator columns.

10. 7. In combination, a plurality of spaced insulator columns which are arranged in such manner that the longitudinal axes thereof are substantially parallel to each other, each of said insulator columns being formed, at least in part, of frangible insulating material; a conducting terminal member supported on each of said insulator columns at one end thereof; a plurality of 15 expulsion fuse devices, each of which includes a tubular member which is closed at one end and is open at the other end during the operation thereof, means for establishing the arc incident to the operation of the device within 20 said tubular member, means for causing a blast of arc extinguishing gas to flow expulsively through said arc to effect its extinguishment, and an outwardly projecting terminal means positioned intermediate the ends of said device; 25 means for supporting each of said fuse devices at the closed end thereof on one of said terminal members; and a common bus bar means which is adapted to engage said outwardly projecting terminal means and to be entirely supported 30 thereon, for electrically interconnecting said fuse devices; said means for supporting said fuse devices positioning each of those devices in such manner that the longitudinal axis of said tubular member substantially coincides with the longitudinal axis of the supporting insulator column 35 therefor in order that substantially all the stresses induced in said insulator columns during the operation of said fuse devices shall be compressive in nature and in order that the blast of arc extinguishing gas incident to the operation of each of the fuse devices shall be directed away from said insulator columns and said bus bar means.

40. 8. In combination, a plurality of spaced insulator columns which are arranged in such manner that the longitudinal axes thereof are substantially parallel to each other, each of said insulator columns being formed at least in part of frangible insulating material; a conducting terminal member having a threaded portion supported on each of said insulator columns at one end thereof; a plurality of expulsion fuse devices, each of which includes tubular means for defining an arc passage which is open at one end during the operation of said device, means for 45 drawing the arc incident to the operation of said device within said arc passage, means for causing a blast of arc extinguishing gas to flow expulsively through said arc passage following each arc drawing operation, a member of conducting material for closing the other end of said arc passage, said member having a threaded portion adapted to cooperate with the threaded portion of said terminal member in order that each of said fusible devices may be supported upon one 50 of said insulator columns in such manner that the longitudinal axis of the arc passage within the device shall substantially coincide with the longitudinal axis of the supporting insulator therefor, and a terminal means of conducting material which projects outwardly from each of

5 said fuse devices intermediate the ends thereof and substantially at right angles to the longitudinal axis thereof; and a common bus bar means which is adapted to engage said outwardly projecting terminal means for electrically interconnecting said fuse devices.

9. In combination, a plurality of insulator units, each of which includes a means of frangible insulating material and a terminal member rigidly supported thereon, and means for electrically interconnecting said terminal members in a predetermined arrangement, said interconnecting means including flexible strap members of conducting material and fuse devices, each of said fuse devices being entirely supported on one 15 of said terminal members, and means carried by each of said fuse devices for engaging and supporting at least one of said flexible strap members in a current-carrying position, said strap conductor being supported in its current-carrying position on each of said fuse devices unaffected by the reaction forces exerted by the opening of any one of said fuse devices which support it.

10. 10. In combination, a plurality of insulator units, each of which includes a means of frangible insulating material and a terminal member rigidly supported thereon, each of said terminal members having a threaded portion formed integral therewith, and means for electrically interconnecting said terminal members in a predetermined sequence, said interconnecting means including strap connectors and fuse devices, each of said fuse devices including tubular means for defining an arc passage, means for establishing the arc incident to the operation of said device within said arc passage, a member of conducting material for closing one end of said arc passage, said member having a threaded portion adapted to cooperate with the threaded portion 40 of one of said terminal members in order that each of said fuse devices may be entirely supported on one of said terminal members, the other end of said arc passage being open at least during the circuit opening position, and means 45 carried by each of said fuse devices intermediate its ends for engaging and supporting at least one of said strap conductors in a current-carrying position, said strap conductor being supported in its current-carrying position on said 50 fuse devices unaffected by the reaction forces exerted by the opening of any one of said fuse devices which carry said means for supporting said strap conductor.

11. 11. In combination, a plurality of insulator columns, a terminal member rigidly mounted on each of said columns, and means for electrically connecting said terminal members including a plurality of expulsion fuses and continuous strap members of conducting material associated therewith, means carried by each of said fuse devices for supporting at least one of said strap members associated therewith in a current-carrying position for providing a continuous conducting path between the fuse devices connected by the strap member, each of said fuse devices being entirely supported upon one of said terminal members and being so positioned with respect to the associated insulator and said strap member that the continuous conducting path provided between 65 said fuse devices by said continuous strap member is unaffected by the reaction forces exerted by the opening of any one of said fuse devices.
